UNITED STATES PATENT OFFICE

152,693

DESIGN FOR A MEDALLION OR SIMILAR ARTICLE

Thomas H. Jones, Washington, D. C., assignor to
the United States of America as represented by
the Secretary of War

Application July 29, 1947, Serial No. 140,577

Term of patent 14 years

(Cl. D29—19)

To all whom it may concern:

Be it known that I, Thomas H. Jones, a citizen of the United States and resident of the city of Washington, in the District of Columbia, have invented a new, original, and ornamental Design for a Medallion or Similar Article, of which the following is a specification, reference being had to the accompanying drawings, forming a part thereof.

Fig. 1 is a front view of the medallion, showing my new design.

Fig. 2 is a side view of the same.

It is understood that my design may be embodied in such articles as a medal, badge, plaque, or sign, without departing from the spirit of my invention.

The essential features of my design are shown in full lines.

I claim:

The ornamental design for a medallion or similar article, as shown and described.

THOMAS H. JONES.
